UNITED STATES PATENT OFFICE.

WILLIAM H. McCLELLAND, JR., OF WILKINSBURG, PENNSYLVANIA, ASSIGNOR TO UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

1,314,884.

Specification of Letters Patent.

Patented Sept. 2, 1919.

Original application filed April 16, 1917, Serial No. 162,259. Divided and this application filed September 6, 1918. Serial No. 252,942.

To all whom it may concern:

Be it known that I, WILLIAM H. McCLELLAND, Jr., a citizen of the United States, residing at Wilkinsburg, in the county of Allegheny and State of Pennsylvania, have invented certain new and useful Improvements in Railway-Traffic-Controlling Apparatus, of which the following is a specification.

10 My invention relates to railway traffic controlling apparatus, and particularly to apparatus for the control of railway switches.

The present application is a division of my co-pending application filed April 16, 15 1917, Serial No. 162,259, for circuit breakers.

I will describe one form of apparatus embodying my invention, and will then point out the novel features thereof in claims.

20 The accompanying drawing is a view, partly diagrammatic, showing one form of traffic controlling apparatus embodying my invention.

25 Referring to the drawing, the reference character 12 designates a railway switch, to which is connected one end of an operating rod 13. Attached to the other end of this rod is a pin or roller 14 which is located in a cam slot 15 in a motion plate 16. An electric motor M' imparts longitudinal movement to the plate 16 through the medium of a gear 17 fixed to the motor shaft 18 and meshing with the toothed edge 19 of the motion plate. Such movement of the plate 16 in either direction causes the pin 14 to follow the course defined by the slot 15, and thereby imparts longitudinal movement to the operating rod 13. By this means, switch 30 12 is shifted from normal position to reverse position or vice versa, according to the direction of movement of the motion plate 16.

The reference character 100 designates a cut-out switch for the motor M' to deenergize the motor after the railway switch has reached either of its extreme positions. This 45 cut-out switch, as here shown, comprises a bar 20 fixed to one end of the plate 16 for movement therewith, such bar being formed with a longitudinally extending slot 21 of a length less than that of the cam slot 15. 50 A switch blade 22 pivoted at 23 is provided with a pin 24 which rides in the slot 21, so that when the bar 20 is moved by the plate 16, blade 22 will be moved to engage con-

tact 25 or 26 according to the direction of movement of the bar. Owing to the length 55 of the slot 21 and the location of the blade 22, the shifting of the blade from contact to contact does not occur until the motion plate 16 has nearly reached the end of its stroke, so that the motor M' may be maintained energized during transit of the switch but will be deenergized after the switch has reached either of its extreme positions.

The switch operating motor M' is supplied with current from a suitable source such as 65 a battery 27, and the supply of current from this battery to the motor is governed in part by the cut-out switch 100 and in part by a circuit controller 200. The circuit controller 200 comprises a switch blade 28 pivoted at 70 29 for engagement with either of a pair of contacts 30 and 31. The switch blade 28 is actuated by a motor M through the medium of a gear 32 fixed to the motor shaft and meshing with a rack bar 33, which latter is 75 in turn connected to the switch blade 28, as shown.

The motor M is supplied with current from a battery 10, and this supply is controlled by a pole-changer 11 operated by a 80 lever 11^a, which lever is usually one of a plurality of similar levers in an "interlocking machine".

Included in the circuit of the switch operating motor M' is a thermostatic circuit breaker C, which device I will now describe. The circuit breaker comprises a base plate B and a top plate T, formed of insulating material and supported in spaced relation by means of rods R. An L-shaped lever L 90 is pivotally mounted for swinging movement upon a lug E formed on the base plate B, and the long arm of the lever L is provided with insulating studs S which carry a flexible contact finger F. This contact finger 95 is adapted to coat with a stationary contact G mounted on an angle bar H, which bar is secured to the upper side of the plate T by a binding post P. Interposed between the short arm of the lever L and the base 100 plate B is an expansible spring K, which spring serves to bias the lever L outwardly, that is, toward such position that the contact F—G is open. The finger F is held, at times, in engagement with contact G against 105 the action of the spring K by means of a

latching device generally indicated at D. This latching device comprises a latching lever d pivotally connected at one end to a link d', which latter in turn is pivotally mounted on the base plate B. The free end of the lever d is formed with a hook d³ for engagement with a pin d⁴ secured to the free end of the long arm of the lever L.

A designates a tripping arm for raising latching lever d away from the lever L. This arm is pivoted at one of its ends to a bracket Z secured to and depending from the top plate T. The tripping arm A is biased upwardly by a contractile spring K', the lower end of the spring being connected to the lever adjacent the free end thereof while its upper end is connected to a screw V adjustably mounted in the top plate T. A block Q formed of insulating material is secured to the upper side of the lever A adjacent its free end to engage the latching lever d, and so to release the latching lever from lever L when the arm A swings upwardly. Upward movement of the lever A is normally prevented by a thermostat X, which, as here shown, consists of a wire formed of material having a large coefficient of expansion, such, for example, as German silver. One end of this wire passes freely through an opening 8 in the bracket Z and is attached to a screw V' adjustably mounted in a second bracket Z'. The opposite end of the wire X is suitably secured to the outer end of the tripping lever A, as shown, such end, however, extending through a block J, secured to the lever whereby the wire is maintained in parallel relation to the lever A throughout its entire length. The brackets Z and Z' are spaced apart by a block Y of insulating material, and are provided with binding posts P' and P³, respectively, arranged upon the upper side of the top plate T, as shown.

By connecting the binding posts P and P' by a conducting wire W, it will be evident from the preceding description that the contact F—G when closed is in electrical communication with the binding post P³ through wire W, post P', bracket Z, arm A, wire X, and bracket Z'.

As shown in the drawing, the circuit breaker C is in set position; that is, the latching device D is in engagement with lever L so that the contact finger F is held in closed position. By properly adjusting the tension of the spring K' and of the wire X, through the medium of their respective screws V and V', the forces exerted upon the tripping lever A by such members may be so controlled that when current of a predetermined value or less flows in wire X, or when current of a higher value flows momentarily in this wire, the arm A is maintained in its inactive position. With the circuit breaker in this position, as-

sume that current of greater than the predetermined value flows through wire X for a considerable length of time. This current will heat the wire to such a degree that the expansion of the wire is sufficient to allow arm A to rise and lift latching lever d away from the pin d⁴, thus allowing contact F—G to open. Current then ceases to flow through wire X, so that this wire cools off and draws arm A down, allowing contact F—G to be reset or closed by the means hereinafter described.

The means for resetting the circuit breaker comprises a disk or wheel N which is operatively connected with the motor M of the circuit controller 200. The disk N is operatively connected to the latching device D by a link U, one end of the link being eccentrically mounted upon the disk while its opposite end is pivotally connected to the link d'. Movement of the disk N either clockwise or counter-clockwise is restricted to substantially one revolution by means of a lug N' formed on the periphery of the disk and adapted to engage a stop O. From this construction and arrangement, it will be seen that when the motor M is energized to rotate in one direction or the other, longitudinal movement is imparted to the latching lever d through the medium of the disk N, rod U and link d', as will be understood. By virtue of this movement of the latching lever, it will be obvious that when the tripping lever A returns to its normal position due to the cooling of the wire X, as previously described, and the motor M is energized, the latching lever is moved forward to cause the hook d³ to engage the pin d⁴, and then rearward to return the lever L and contact finger F to their normal positions, as shown in the drawing. It is to be noted that before the lever L can be returned to its normal position to close contact F—G it is necessary that the thermostat X, and consequently the lever A, shall have returned to their normal positions, as otherwise the latching lever d when moved forward would fail to engage the pin d⁴ on lever L.

The operation of the entire apparatus is as follows: In the drawing, the switch 12 is shown in the "normal" position, and the other parts of the apparatus are shown in the positions corresponding to this position of the switch. When it is desired to move the switch 12 to its "reverse" position, pole-changer 11 is manually reversed, whereby current from battery 10 is supplied to motor M in such direction as to cause counter-clockwise rotation of pinion 32 and disk N. The rotation of disk N causes operation of latching device D to open the contact F—G and again close this contact. The rotation of gear 32 causes rack bar 33 to be drawn to the right, thereby shifting switch blade 28 from contact 31 to contact 30. When both

of these contact operations have been completed, current is supplied to the motor M' through the following circuit: from battery 27, through wires 36 and 37, contact 30, blade 28, wire 38, motor M', wire 35, binding post P⁸, bracket Z', screw V', wire X, tripping lever A, bracket Z, binding post P', wire W, binding post P, contact G, contact finger F, wire 34, blade 22, contact 25, wires 39 and 10 40 to battery 27. Although current is now traversing the thermo-wire X, this wire is so proportioned that the heat generated therein by the current which flows while the motor M' is running is insufficient to expand the wire to such degree as to cause arm A to release the circuit breaker. Furthermore, although a comparatively heavy current flows through wire X while the motor M' is starting, the duration of this heavy current 15 20 is insufficient to cause wire X to expand sufficiently to trip the circuit breaker. As the motion plate 16 approaches the end of its stroke, the end of the slot 21 engages pin 24, causing switch blade 22 to swing into engagement with contact 26, thereby excluding the battery 27 from the motor circuit and so causing deenergization of the motor M'.

To throw the switch 12 from reverse to normal position, pole-changer 11 is returned 30 to the position shown in the drawing, whereby motor M will be energized to rotate in clockwise direction. The consequent return of switch blade 28 to the position shown in the drawing will cause motor M' to be 35 40 reversely energized through the following circuit: from battery 27, through wires 40 and 41, contact 31, blade 28, wire 38, motor M', wire 35, etc., to blade 22, contact 26, wires 42 and 36 to battery 27.

40 If the motor M' should stall for any reason while moving the switch, an excessive current will traverse the motor circuit, but such excessive current will heat the thermostatic wire X to such a degree as to expand the same sufficiently to cause arm A to trip the circuit breaker. Contact F—G then being opened, the circuit for the motor M' is of necessity disrupted, thus preventing injury to the motor or to other apparatus in 45 50 the motor circuit.

Should the stalling of the motor M' be caused by some obstruction between the switch rails and track rails, it is obvious that after the wire X has cooled sufficiently, the 55 60 pole-changer 11 may be shifted, thus re-setting the circuit breaker and thereby causing the motor M' to return the switch operating mechanism to its original position ready to make another attempt to crush the obstruction.

Although I have herein shown and described only one form of railway traffic controlling apparatus embodying my invention, it is understood that various changes and 65 70 modifications may be made therein within

the scope of the appended claims without departing from the spirit and scope of my invention.

Having thus described my invention, what I claim is:

1. In combination, a railway switch operating mechanism including a motor, a source of energy for said motor, a circuit controller interposed between said motor and said source of energy, a second motor 70 75 for actuating said circuit controller; a circuit breaker, a thermostat included in said circuit breaker and connected in series with the first-mentioned motor, and means actuated by said second motor for closing said 80 circuit breaker.

2. In combination, a railway traffic controlling mechanism including a motor and a source of current therefor, a circuit controller interposed between said motor and 85 source of current, a second motor for actuating said circuit controller; a circuit breaker comprising a contact for controlling said first mentioned motor circuit and biased to an open position, a latching device for 90 said contact, a thermostat connected in series with said first mentioned motor and capable of actuating said latching device to release said contact, and means operable by said second motor under predetermined conditions 95 for restoring said latching device to latching engagement with said contact.

3. In combination, a railway switch, a switch motor for causing reverse movements thereof, a circuit for said motor including 100 a source of current and a circuit breaker contact biased to open position, a latch coöperating with said contact for closing the contact and holding it in closed position, a circuit controller including a second motor 105 capable of reverse operations for governing the supply of current to said switch motor from said source, a thermostat included in the circuit of said switch motor for releasing said latch to allow said circuit breaker contact to open, and means controlled by said second motor and operating each time that the circuit controller is reversed to actuate said latch to close the circuit breaker contact. 110 115

4. In combination, a railway switch, a switch motor for causing reverse movements thereof, a circuit for said motor including a source of current and a circuit breaker contact biased to open position, a thermostat included in said motor circuit for causing said contact to open when an excessive current flows in said circuit for an excessive length of time, a circuit controller capable of reverse operations for governing the supply of current to said motor from said source, and means controlled by said circuit controller for closing said circuit breaker contact each time that the circuit controller is reversed. 120 125 130

5. In combination, a railway switch, a switch motor for causing reverse movements thereof, a circuit for said motor including a source of current and a circuit breaker contact biased to open position, a thermostat included in said motor circuit for causing said contact to open when an excessive current flows in said circuit for an excessive length of time, a circuit controller adjacent said switch for governing the supply of current to said motor from said source, an

interlocking machine including a lever for control of said circuit controller, and means controlled by said circuit controller for closing said circuit breaker contact each time 15 that the circuit controller is reversed.

In testimony whereof I affix my signature in presence of two witnesses.

WILLIAM H. McCLELLAND, JR.
